CLAYTON S. HAM, OF SAN FRANCISCO, CALIFORNIA, ASSIGNOR TO AARON TURNER, OF OAKLAND, CALIFORNIA.

ELECTRIC SELF-WINDING CLOCK.

Application filed January 17, 1925. Serial No. 3,073.

This invention relates to electrically-operated self-winding clocks of the hour-wind type and the primary object of the invention is to provide such a clock with various improved features. In clocks of this type an electro-magnetically operated armature is usually provided with a ratchet pawl which operates on a ratchet wheel to wind the clock spring. The circuit to the electro-magnet is periodically closed by a switch operated automatically from the hour hand shaft. My invention contemplates such a mechanism and combines therewith further means for positively assuring that the switch will remain closed until the spring has been wound a predetermined amount. One object of my invention is to provide a mechanism for performing this function.

Another object of my invention resides in providing an improved make and break system for interrupting the circuit to the electro-magnet. Ordinarily such a system comprises a pair of contacts normally in the closed position, the attraction of the armature being adapted to break such circuit. My improved system contemplates a pair of spring contacts normally in the open position, the weight of the armature normally acting thereon to close the contacts.

For the successful functioning of a device of this type, particularly with alternating currents, it is essential that the contacts should remain closed for a very definite period of time and that the break should be substantially instantaneous. I accomplish this object by the use of an improved interrupting switch which has combined therewith a bumper spring for taking the falling shock of the armature directly through the switch contacts. Heretofore the armature shock has been absorbed by a bumper spring placed beneath the armature. The combining of the bumper spring with the switch contacts establishes a direct and absolutely dependable relation between the closing of the contacts and the stopping of the falling movement of the armature. This construction particularly adapts the device for use with alternating current and also makes the mechanism adjustment easily convertible for use with either alternating current or direct current as hereinafter described.

With the above and other objects in view, my invention consists in the features of construction and operation set forth in the fol-

lowing specification and illustrated in the accompanying drawings. In such drawings annexed hereto and forming a part of this specification, I have illustrated certain specific embodiments of my invention in a self-winding clock, but it will be understood that the invention can be otherwise embodied and that the drawings are not to be construed as defining or limiting the scope of the invention, the claims appended to this specification being relied upon for that purpose.

Referring to the figures of the drawings:—

Fig. 1 is a rear elevation of a self-winding clock embodying my invention, the rear plate of the clock being removed to better illustrate the working parts.

Fig. 2 is an edge view thereof.

Fig. 3 is a fragmentary sectional view through the clock along the hour hand shaft.

Fig. 4 is a detail view showing one form of my interrupting switch.

Fig. 5 is a like view illustrating another form thereof.

Fig. 6 is a fragmentary view illustrating a modification of my invention.

Fig. 7 is a fragmentary face view of a modified form of the switch-controlling mechanism shown in Fig. 1.

Fig. 8 is a like view showing the parts in another section.

Fig. 9 is a longitudinal sectional view there-through.

Referring first to Figs. 1 to 5 of the drawings, 1 and 2 indicate the front and rear supporting plates of a clock. The hour hand shaft 3 of the clock is supported by the plates and has the inner end 4 of the main spring 5 connected thereto. The outer end 6 of the spring is connected to a gear 7 loose on the shaft. A small pinion 8 rigid with a ratchet gear 9 is in mesh with the gear 7. This ratchet gear is adapted to wind the spring as hereinafter described.

A two-pole electro-magnet 10 is provided for winding the spring 5. The armature 11 for the magnet is mounted on the lower end of a frame 12 pivoted at 13 and a pin 14 thereon slidably engages in a slot 15 in the free end of an arm 16 loosely mounted on the shaft of the ratchet gear 9. A pawl 17 carried by the arm 16 engages the ratchet teeth of this gear. Rocking movement of the frame 12 is adapted to rock the arm 16

and rotate the gear 9 through the pawl 17. A pawl 18 engages the gear to prevent backward rotation thereof. A pair of shock absorbing or bumper springs 19 and 20 are provided for assisting in the reverse movements of the armature.

Two binding posts 21 and 22 are provided on an insulating plate 23 secured to the plate 2. The electric circuit extends from the post 21 through a switch 24, lead 25, electro-magnet 10, lead 26 and a switch 27 to the post 22. The switch 24 is the main switch in the circuit and controls the operation of the winding mechanism. The switch 27 is an interrupting make and break switch. The electro-magnet 10 intermittently attracts the armature to rock the same about the shaft 13. The novel features of my invention center around these two switches 20 and their cooperating mechanism.

Switch 27 is illustrated in two forms in Figs. 4 and 5. The construction of these two forms is substantially the same, the only difference being in the position of one 25 of the contact elements as hereinafter described. This switch comprises two base conductors 28, having mounted thereon two spaced substantially parallel spring arms 29 and 30. Contact points 31 are provided on the free ends of these arms. The arm 29 is backed up by a bumper or shock-absorbing spring 32 and plates 32' provide the usual rests for the arms. Among the functions performed by these rests may be mentioned: 35 (1) Permitting the adjustment of spring tension by curving the spring before assembling. (2) Insuring a more positive and permanent adjustment of contacts. (3) Preventing the breaking of the contact springs 40 by the vibrating of the same after they spring apart. The end of the arm 30 is preferably bent over at 33 for the purpose hereinafter described.

The switch 27 is mounted in the manner shown in Fig. 1. A roller 34 of insulating material, on the upper end of the armature frame 12, contacts with the bent over portion 33 of the arm 30, the weight of the armature 11 or the action of spring 19 being such that the arm 30 is normally held in the switch-closing position as illustrated. It will, of course, be understood that the arm 11 can be operated in positions other than that illustrated in the drawings and 55 wherein gravity would not operate to close the contacts. In such a position a spring operating to force the armature away from the poles of the magnet, like the spring 19, can be added and adjusted to perform this function. The electric energy passing through magnet 10 raises the armature 11 and draws the roller away from the arm 30. The arm 30 thereupon moves back to its normal position and opens the switch. This 60 breaking of the circuit releases the armature

which again falls and closes the switch. This making and breaking of the circuit takes place at a very rapid rate and the fact that the switch is normally in the open position leaves the switch closed only for the instant of time held in such position by the roller 34.

The mechanism shown in Figs. 1, 2 and 3 for controlling the main switch 24 will now be described. The V-shaped switch- 75 closing lever 35 is pivotd at 36, the two arms of the lever being held frictionally together and adjustable. The upper branch of this lever carries a pin 37 beneath the lower arm of the switch. The lower branch of this 80 lever carries a flange 38 which extends laterally over a disc 39 rigid with the gear 7 and over a cam 40 loose on the shaft 3. A notch 41 is provided in the disc for receiving the flange 38 and when the flange is seated 85 therein, as illustrated in Fig. 1, the switch is open. When the flange is on the high part of the cam 40 or the periphery of the disc 39 the switch is held closed. The use of the adjustable pivoted lever 35 permits 90 accurate controlling of the switch contacts and allows the locating of the contacts at any convenient place.

A pin 42 extends through the cam 40 and is adapted to cooperate on one side with 95 a pin 43 seated radially in the shaft 3 and on the opposite side with a radially extending arm 44 carried loosely on the shaft 3 between the cam 40 and the disc 39. A pin 45 seated in the disc is also adapted to cooperate with the arm 44. The pin 43 is adapted to cooperate with the pin 42 to rotate the cam 40 from the shaft 3 and the pin 45 is adapted to cooperate with the arm 44 and pin 42 to rotate the cam 40 from the 100 disc 39, all of which is hereinafter more fully described.

In its normal operation, the mechanism as above described is adapted to automatically and priodically wind the spring 5 each hour. Assuming that the spring is partially wound up and that the parts are in the position illustrated in Fig. 1, the operation is as follows:

As the clock continues to run, the hour hand shaft 3 rotates in the direction of the arrow and the pin 43 engages against the pin 42 and rotates the cam 40 therewith. Engaging of the cam beneath the flange 38 lifts the lever 35 and closes the switch 24. 115 The armature frame 12 is thereupon oscillated and through the pawl 17 and the ratchet gear 9 rotates the gear 7 in a direction to wind the spring 5 (see arrow Fig. 1). As the notch 41 leaves the flange 38, the 120 flange is still resting on the cam 40 which is slightly higher than the disc 39. The periphery of the disc, however, is in position to absolutely prevent the opening of the switch until the notch again registers with 125 130

the flange. The cam 40 is holding the flange and must be moved therefrom to again permit the flange to drop into the notch 41. As the disc nears the completion of one rotation 5 the pin 45 operates through the arm 44 and pin 42 to move the cam from beneath the flange. The flange thereupon drops into the notch and permits the switch 24 to open. The spring has thereupon been wound one 10 rotation and will again automatically repeat such winding when the shaft 3 carries the cam 40 beneath the flange 38.

If the electric power is off when the cam 40 lifts the lever 35, the cam, being 15 gradually carried on by the running of the clock, again comes around one hour later and closes the switch as before. Upon this second closing of the switch the cam cannot be carried further since the pin 43 comes 20 against the pin 42 which in turn hits the arm 44 and carries the same against the pin 45 on the disc 39 and gear 7. If the electric power is still off, the clock will stop at this point but will be rewound when the current 25 again comes on since the cam 40 remains in position holding the switch closed. Since the cam passed by the flange 38 once when the current was off, the winding of the clock from this point will rotate the gear 7 two 30 rotations before the pin 45 will push the cam beyond the notch 41 and permit the flange to drop thereinto.

If the current goes off during the winding operation, the continued running of the clock 35 will cause the cam 40 and the other parts to assume the completely run-down position described above, except that the cam 40, instead of stopping in the switch-closing position described above, will rest at some point 40 in its rotation from this position which is equal to the amount or proportion of a turn which the gear 7 was carried in the last incompletely rewinding operation. It is to particularly insure the rewinding of the 45 clock in the last described situation that the disc 39 has been devised.

Rewinding when the switch is held closed by the disc 39 takes place in the following manner: The incompletely portion of the rotation of the gear 7 is accomplished. Then 50 as the shaft 3 revolves, the cam 40 is carried forward by the pin 43 until the cam closes the switch at which time the gear 7 makes two rotations to its normal fully wound-up 55 position. At this position the pin 45 pushes the cam beyond the notch 41 and permits the flange 38 to drop thereinto.

From the above description it will be seen 60 that the disc 39 positively assures that the switch 24 will be held closed until the spring 5 has been wound the predetermined amount of one rotation. Should the electric current be turned off during the winding operation, the continued running of the clock will have 65 no effect on the switch. When the current

again comes on the clock will continue its re-winding in the same manner as though no interruption had taken place.

In Figs. 7, 8 and 9, I have shown a modification of the above mechanism whereby I 70 insure a greater margin of safety in case of interruption of current supply. The mechanism above described has a margin of one hour after the clock becomes run-down to the rewinding position, that is, should the 75 clock fail to rewind at the regular rewinding period, the same will rewind an additional hour at the next rewinding. In Figs. 7, 8 and 9, I show a Geneva stop mechanism in place of the pin 45 and the arm 44 of 80 Figs. 1, 2 and 3. This mechanism as illustrated will rewind one to three additional hours and it will be understood that the mechanism can be constructed to rewind a more or less number than this if desired. 85

In this form of the invention, I substitute a disc 39' for the disc 39. The disc 39' is provided with a forwardly projecting annular flange 46 slotted at 47 to receive therethrough a Geneva stop gear 48 carried on the gear 7. A one-tooth gear 49 is carried with a cam 40' on a sleeve 50 loose on a sleeve 51 also loose on the hour hand shaft 3. The gear 49 and cam 40' are both secured rigidly to the sleeve 50. The one tooth 52 of the gear 49 is adapted to cooperate with tooth recesses 53 in the gear 48 and the periphery of the gear 49 is adapted to cooperate with arcuate cut-out portions 54 in the gear 48. The flange 46 is also cut away at 55 to permit the dropping of the flange 38' of the switch arm 35' thereinto as hereinafter described.

In Fig. 7 the mechanism is illustrated in substantially the fully wound-up position. The gear 7 is still rotating in the direction of the arrow and is carrying the one-tooth gear 49 and cam 40' therewith. The flange 38' of the switch arm is about to ride off the cam 40' and drop into the notch 55 cut into 110 the flange 46 of the disc 39'. When such action takes place the switch 24 is opened and the winding operation stopped.

As in the mechanism of Fig. 1, upon continuous running of the clock, the pin 43 engages the pin 42' and rotates the cam 40'. Engaging of the cam beneath the flange 38' lifts the switch arm 35' and closes the switch. The clock thereupon performs its winding operation, the gear 7 revolving in 120 the direction of the arrow. At the end of one rotation the flange 38' drops into the notch 55 and the switch opens in the manner above described. Should the current supply be off when the cam closes the switch, the tooth 52 will engage in the first tooth recess 53 and rotate the gear 48 one tooth. Continued running of the clock carries the cam around again and again closes the switch. If the current supply is on, the clock will 130

rewind the gear 7 two rotations. If the current supply is off the tooth 52 will engage in the second tooth recess 53 and rotate the gear 48 another tooth. This operation can 5 continue until the parts reach the position illustrated in Fig. 8, when, due to the tooth 52 engaging against the periphery of the gear 48, the parts will be locked. In this position the cam is holding the switch closed 10 and when the current comes on, the winding gear 7 will be rotated four turns, stopping in the position illustrated in Fig. 7.

In Figs. 4 and 5, I have illustrated my improved interrupting switch 27, having combined therewith a bumper spring 32 for taking the falling shock of the armature directly through the switch contacts as has been heretofore referred to. In Fig. 4 the arm 29 is bent toward the arm 30 to bring 20 the contact points 31 relatively closer together than in Fig. 5. As has been described, the roller 34 of the armature frame 12 operates against the portion 33 of the arm 30 to bring the contacts together. In 25 Fig. 4, the contact will be made much quicker than in Fig. 5 and the arm 29 will be bent backward until contact is made with the bumper spring 32. Also when the roller 34 is moved in the opposite direction, the 30 arm 29 will follow up the arm 30 and retain the contact until the arm 29 is in the position illustrated in Fig. 4.

In Fig. 5 contact is made near the end of the movement of the arm 30. The switch 35 shown in Fig. 4 is adapted to provide a relatively long make or contact and the switch shown in Fig. 5 is adapted to provide a relatively short make or contact. The switch of Fig. 4 is particularly adapted to 40 be used in connection with a direct current circuit and the switch of Fig. 5 is particularly adapted to be used with an alternating current circuit.

Heretofore, clocks of the type defined 45 herein have not been adapted for use with alternating current circuits since the make and break switches have been such that the contact time has been so long that the pull of the alternating current magnet is too 50 weak or, when adjusted short enough to give necessary pull, there is danger of not making a contact at all and consequently failing to operate. Therefore, for alternating electric current, it is not practical to use the 55 old style construction having an armature bumper spring and contacts as two separate and independent units. For this reason clocks of this type have not heretofore been manufactured or sold for use with alternating current circuits. As has been stated, I eliminate this objection by combining the 60 make and break switch and the bumper spring into one unit whereby the force resisting the falling of the armature operates 65 entirely through the contact points 31. This

object is accomplished by backing up spring arm 29 with a bumper spring 32, this spring being adapted to resist the falling of the armature as shown in Fig. 1.

When the switch 24 closes a circuit allowing alternating current to flow through the magnet coils there is a momentary rush of current with rapidly decreasing volume accompanied by a corresponding cycle of pull on the armature. This is very different from the action of a direct current magnet. An instantaneous break as obtained from a practically rigid contact has a large spark and a small pull on the armature. A contact with a very stiff back spring gives a somewhat smaller spark and a maximum pull. A moderately stiff back spring, such as I use at 32, gives a very slight spark with a good steady pull. Weakening the spring a little more tends to reduce the spark and make the pull too weak to give a steady action.

As illustrated in Fig. 1, I preferably retain the old style bumper spring 20 to assist in taking some of the shock of the armature though this spring can be entirely eliminated if desired. From the statements above made it will be understood that the successful operation of a device of this type depends upon establishing a very fine and dependable relation between the closing of the contacts and the stopping of the falling movement of the armature. The bumper spring 32 assists in both these operations and, therefore, to obtain this fine relation it is necessary to make the spring 32 of the proper strength. When the contacts are closed by the falling of the armature the spring 32 is bent back in resisting the falling action. The contacts are, of course, held closed during this time. Stiffening the spring will stop the armature 100 quicker and shorten the contact time. The character of the bumper spring 32, therefore, definitely times the contact and the contact is extremely sure since the entire resisting force of stopping the armature is 105 through the contact points.

It should be understood that in the above described adjustments the other available elements vital to the oscillation of the armature are in each case made to give the best 110 possible action. These elements are substantially as follows:

1. Winding of the magnet coils.
  2. Weight of the armature.
  3. Tension and position of the upper 120 bumper spring 19.
  4. Position of the armature relative to the upper bumper spring 19 with the armature resting on the contacts and backed up by the bumper spring 32.
  5. Position of the magnet pole-pieces with respect to the armature and bumper springs.
  6. Load or tension of the clock spring 5 to be wound.
- In Fig. 6 I have shown a modified form 130

of my invention. In this construction the armature 56 which is attracted by the poles 57 of the electro-magnet 58 is mounted directly on a frame 59 pivoted to the shaft 60 of the ratchet gear 61. A pawl 62 carried by the armature operates on the gear 61 and a second pawl 63 prevents backward rotation of the gear. The interrupting switch 64 is mounted on an arm 65 adjustable at 66 about a pivot 67. The weight of the armature normally holds the contacts 68 closed, a spring 69 assisting in the armature movements. The spring 69 is located between the armature 56 and a plate 70, the plate being adjustable at 71 about a pivot 72 to vary the position of the spring relative to the armature. The operation of this construction is substantially the same as that above described.

Having thus described my invention, what I claim and desire to secure by Letters Patent is:

1. A self-winding spring-operated mechanism comprising the combination of a shaft and a coil spring having one end secured to the shaft, means loosely mounted on the shaft and having the other end of the spring connected thereto, electrically operated means cooperating with the first mentioned means to wind the spring, a switch for controlling the electrically operated means, means automatically operated by the shaft for closing the switch, and means cooperating with the first mentioned means for positively assuring that the switch will remain closed until the spring has been wound a predetermined amount.
2. A self-winding spring-operated mechanism comprising the combination of a shaft and a coil spring having one end secured to the shaft, means loosely mounted on the shaft and having the other end of the spring connected thereto, electrically operated means cooperating with the first mentioned means to wind the spring, a switch for controlling the electrically operated means, and means carried by the first mentioned means and adapted to keep the switch closed should the electric power be interrupted during the winding operation.
3. A self-winding spring-operated mechanism comprising the combination of a shaft and a coil spring having one end secured to the shaft, a gear loosely mounted on the shaft and having the other end of the spring connected thereto, electrically operated means cooperating with the gear to wind the spring, a switch for controlling the electrically operated means, means including a cam carried by the shaft for closing the switch, a disc carried by the gear and having a notch therein for receiving the switch closing means in a manner permitting the switch to open, the cam being adapted to close the switch when the cam reaches a pre-determined position and the disc being adapted to rotate during the winding operation and to assure that the switch will be held closed until the gear makes a predetermined rotation and brings the notch around to its initial position whereupon the switch-closing means drops thereinto.
4. A self-winding spring-operated mechanism comprising the combination of a shaft and a coil spring having one end secured to the shaft, a gear loosely mounted on the shaft and having the other end of the spring connected thereto, electrically operated means cooperating with the gear to wind the spring, a switch for controlling the electrically operated means, a cam loosely carried by the shaft, a disc rigidly carried by the gear and having a notch therein, switch-closing means in the path of the cam and disc, means carried by the shaft for moving the cam to a position closing the switch, the disc being adapted to rotate during the winding operation and to assure that the switch will be held closed until the gear makes a predetermined rotation and brings the notch around to its normal position whereupon the switch-closing means drops thereinto, and means carried by the gear for moving the cam beyond the switch-closing means.
5. A self-winding spring-operated mechanism comprising the combination of a shaft and a coil spring having one end secured to the shaft, means loosely mounted on the shaft and having the other end of the spring connected thereto, electrically operated means cooperating with the first mentioned means to wind the spring, a switch for controlling the electrically operated means, means automatically operated by the shaft and including a suitably pivoted lever having one end adjacent the shaft and the other end adjacent the switch for transmitting the switch-closing motion from the shaft to the switch at any convenient location, and means cooperating with the first mentioned means for keeping the switch closed should the electric power be interrupted during the winding operation.
6. A self-winding spring-operated mechanism comprising the combination of a shaft and a coil spring having one end secured to the shaft, means loosely mounted on the shaft and having the other end of the spring connected thereto, electrically operated means cooperating with the first mentioned means to wind the spring, a switch for controlling the electrically operated means, means automatically operated by the shaft for periodically closing the switch, and means cooperating with the first mentioned means for positively assuring that the switch will remain closed until the spring has normally been wound a predetermined amount, the last stated means including cooperating mechanism whereby the spring will be auto-

matically wound more than the predetermined amount at a later winding should the winding mechanism fail to function at one of the periodic winding periods.

- 5 7. A self-winding spring-operated mechanism comprising the combination of a shaft and a coil spring having one end secured to the shaft, a gear loosely mounted on the shaft and having the other end of the spring 10 connected thereto, electrically operated means cooperating with the gear to wind the spring, a switch for controlling the electrically operated means, means including a cam carried by the shaft for closing the switch 15 at a predetermined position in one rotation of the shaft, and means for causing the switch to open after one rotation of the gear, the last stated means including cooperating mechanism whereby the predetermined rotation 20 of the gear may be automatically increased to three or more rotations thereof to wind the spring to its normally wound up position should the electric power have failed to function at the regular winding 25 period.

8. A self-winding spring-operated mechanism comprising the combination of a shaft and a coil spring having one end secured to the shaft, a gear loosely mounted on the 30 shaft and having the other end of the spring connected thereto, electrically operated means cooperating with the gear to wind the spring, a switch for controlling the electrically operated means, means including a cam 35 carried by the shaft for closing the switch, an element carried by the gear and having a notch therein, the last stated means including a V-shaped lever having one arm co-operating with the switch and the other arm 40 cooperating with the cam, the cam being adapted to close the switch when the cam reaches a predetermined position and the element being adapted to rotate during the winding operation and to assure that the 45 switch will be held closed until the gear makes a predetermined rotation and brings the notch around to its initial position whereupon the said other arm of the lever drops thereinto and permits the switch to 50 open.

9. An electrically operated winding mechanism comprising the combination of an

electro-magnet, a pair of contacts in the electro-magnet circuit, the contacts normally tending to move to the open position, an 55 armature cooperating with the electro-magnet and normally in a position acting on one of the contacts to hold the contacts closed, a wheel, means engaging the wheel and operated by movement of the armature to rotate the wheel in one direction, the construction being such that attraction of the armature permits the contacts to open and the falling of the armature closes the contacts, and resilient means cooperating with the other contact for receiving the falling shock of the armature through the contacts.

10. An electrically operated winding mechanism comprising the combination of an electro-magnet, a pair of contacts in the electro-magnet circuit, the contacts normally tending to move to the open position, an armature cooperating with the electro-magnet and pivoted in such a manner that the weight of the armature normally holds the contacts closed, a wheel, means engaging the wheel and operated by movement of the armature to rotate the wheel, the construction being such that attraction of the armature permits the contacts to open and the falling of the armature closes the contacts, and resilient means cooperating with the contacts for receiving the falling shock of the armature through the contacts.

11. An electrically operated winding mechanism comprising the combination of an electro-magnet, a pair of spring arms in the electro-magnet circuit, a pair of cooperating contacts on the free ends of the arms, the arms normally tending to separate the contacts, an armature cooperating with the electro-magnet and having means normally engaging one of the arms in a manner holding the contacts closed, a wheel, means engaging the wheel and operated by movement of the armature to rotate the wheel, the construction being such that attraction of the armature permits the contacts to open and the falling of the armature closes the contacts, and a bumper spring engaging the rear face of the other arm for receiving the falling shock of the armature through the contacts.

CLAYTON S. HAM.
